DRY SHAVER WITH HAIR RECEIVING
RECEPTACLE

Ingvar Lonne, Burbank, Calif.

Application April 29, 1946, Serial No. 665,914

7 Claims. (Cl. 30—41)

1

My invention relates to a mechanically operated shaver, and particularly to one which may be readily cleaned.

One of the principal objects of this invention is to provide a shaver of this class having shaving or shearing means at one end and means at said end for covering the hair receiving receptacle, and in which such receptacle may be readily uncovered by the fingers of the hand gripping the shaver for blowing out or otherwise removing the hair in the receptacle.

Another important object of this invention is to provide shaving or shearing means at one end of the shaver, which is open at the opposite ends, and in which the ends are normally closed by slideable gates at the edges of the shaver, and further in which the gates are slideable backwardly from the end of the shaver for uncovering such open ends of the shaving means.

An important object of this invention also is to provide a novel mounting for such slideable gates so that they present an appearance of being an integral or rigid part of the frame.

A further important object of this invention is to provide novel, simple and resilient means for holding the slideable gates in either closed or open position.

With these and other objects in view, as will appear hereinafter, I have devised a shaver of this class having certain novel features of construction, combination, and arrangement of parts and portions, as will be hereinafter described in detail and particularly set forth in the appended claims, reference being had to the accompanying drawings and to the characters of reference thereon, which form a part of this application, in which:

Fig. 1 is a side view of an electric razor or shaver, embodying my invention in one form;

Fig. 2 is an edge view thereof;

Fig. 3 is an enlarged fragmentary partial side and partial sectional view of the head or shaving end thereof;

Fig. 4 is a fragmentary transverse sectional view thereof, taken through 4—4 of Fig. 3;

Fig. 5 is a sectional view thereof, taken through 5—5 of Fig. 3;

Fig. 6 is a fragmentary side view of one edge portion of my shaver in a slightly modified form of construction;

Fig. 7 is a sectional view taken at 7—7 of Fig. 6, showing the inner side of the gate construction, in a slightly modified form, for the removal of hair from the shaver;

Fig. 8 is an end view of the base of the outer shear members;

2

Fig. 9 is a view similar to Fig. 6, showing the gate construction in another modified form; and, Fig. 10 is a sectional view similar to Fig. 7, but taken at 10—10 of Fig. 9.

5 My razor or shaver, as shown in Figs. 1 and 2 of the drawings, is similar in appearance to the electric shaver now in use. It is enclosed in a casing 1, which serves as a hand grip and as the frame for the shaver. It is relatively wide at its 10 head end, as indicated by 1^a, and at this end is located the shaving means, which consists of an outer shear member 2, and an inner shear member 3. The outer shear member is channel shaped, that is, U-shaped in cross-section, as shown in Fig. 4. The flanges 2^a fit within a channel 1^b at the shaving end of the frame, as shown best in Figs. 1 and 2. In the channel portion 2^b of the shear member 1 is located the inner shear member 3, which is also of U-shaped cross section. The inner side of the connecting portion 2^c at the outer end of the outer shear member 2 is engaged by the corresponding connecting portion 3^a at the outer end of the inner shear member 3, forming the shearing means for the shaver.

20 The opposite ends of the channel portion 2^b of the outer shear member are open, permitting the hair or bristles cut by the shear member to drop or be blown from the pocket inwardly from the shearing portions of the shear members.

25 At the inner portion of the outer shear member, between the flanges 2^a, and inwardly from the inner end of the inner shear member is secured a base member 4, which is hollow and of U-shaped cross-section, the connecting portion 4^a being positioned at the inner end of the inner shear member. The ends of the base 4 are closed by a wall 4^b, as indicated in Fig. 8, and this wall is provided with longitudinal slots 4^c, which will be hereinafter referred to.

30 At the inner end of the inner shear member 3 is also provided a base 5, as shown in Fig. 4.

35 At the opposite edges of the shaver are gates 6, which are relatively long, the outer ends of 45 which normally cover the open ends of the outer shear member, as shown best in Fig. 3. These gates conform in shape to the edges of the shaver, as shown best in Fig. 1. These gates are longitudinally slideable in grooves 6^c in the edges of the 50 frame. The gates are provided with reduced portions or tenons 6^a, which are longitudinally slideable in grooves formed between the flanges 2^a of the outer shear member. The outer sides of the gates have knurled or serrated portions 6^b 55 to facilitate the shifting of the gates, in the grooves above mentioned, in order to uncover and

cover the openings at the ends of the outer shear member.

The shear members have inwardly extending lugs or arms 6^d, which extend into the interior of the shaver and preferably through the slots 4^c, mentioned above, and are retained in position by such arms 6^d.

The gates are retained in such sliding positions by spring means shown in different forms in Figs. 3, 6, and 10. The spring means shown in Fig. 3 consists of a pair of coiled springs 11, which are located inwardly of the shearing means of the shaver, and specifically within the channel of the base 4, the coiled portions 11^a of these springs lying against the inner side of the connecting portion 4^a of such base and extending longitudinally thereof. The inner ends 11^b of these springs are secured to ears 4^d extending inwardly from the cross portion of the base, as shown in Fig. 3. The opposite or outer ends of the springs have straight shanks 11^c, which are threaded through eyes in downwardly extending lugs 4^e, extending inwardly from the cross portion of the base 4. The outer ends of the shanks 11^c are bent downwardly forming readily yieldable arms 11^d, which extend through holes at the inner ends of the inwardly extending arms 6^d of the gates 6. In this manner the gates are resiliently held in their variously shifted positions against the sides or edges of the shaver. Such construction permits greater resilient force for holding the gates against the edges of the shaver when the gates are in position to cover the openings at the opposite ends of the outer shear member.

The opposite edges of the shaver are inclined in such manner that they converge toward the shaving end of the razor, permitting the gates 6 to slide in such inclined directions, normally tending to hold the gates in closed position over said openings.

The modifications in Figs. 6 and 7 show studs 21 extending inwardly from the inner side of the gates at approximately the median portion between the ends. These studs extend through the slots 4^c in the base 4, which hold the studs in such position by leaf spring members 22 which are threaded over the studs. These spring members are held in position and under tension against the inner sides of the end walls 4^b of the base by circular spring clips 23 positioned in grooves at the inner end portions of the studs 21.

In the modification shown in Figs. 9 and 10 there is substituted a coil spring 24, which is positioned around the portion of the studs extending through the slots 4^c and are held in position and compression by spring clips 23.

Though I have shown and described a particular construction, combination, and arrangement of parts and portions, and certain modifications thereof, I do not wish to be limited to the same, but desire to include in the scope of my invention the construction, combination, and arrangement substantially as set forth in the appended claims.

I claim:

1. In a shaver of the class described, a frame having a hollow shear member at one end transversely of the frame, the ends of the shear member being open, gates slidably mounted at the opposite sides of the frame normally covering the open ends, said gates being slidable backwardly from the end of the frame to uncover the openings, and a coil spring for each of the gates, the inner end of each spring being secured within and to the median portion of the frame and so

mounted as to be elongated outwardly toward said sides, and provided at the outer ends with downwardly bent arms, said gates having intermediate their upper and lower ends inwardly extending arms, each of the latter arms being mounted and longitudinally slideable on the arm of one of the springs and resiliently held by the respective spring against the corresponding end of the frame.

2. In a shaver of the class described, a frame having a hollow shear member at one end transversely of the frame, the ends of the shear member being open, gates slidably mounted at the opposite sides of the frame in directions converging toward the shear end of the frame, said gates normally covering the open ends, said gates being slideable backwardly from the end of the frame to uncover the openings, and a coil spring for each of the gates, the inner end of each spring being secured within and to the median portion of the frame and so mounted as to be elongated outwardly toward said sides, and provided at the outer ends with downwardly bent arms, said gates having intermediate their upper and lower ends inwardly extending arms, each of the latter arms being mounted and longitudinally slideable on the arm of one of the springs and resiliently held by the respective spring against the corresponding end of the frame.

3. In a shaver of the class described, a frame having a hollow shear member at one end transversely of the frame, the ends of the shear member being open, gates slidably mounted at the opposite sides of the frame normally covering the open ends, said gates being slideable backwardly from the end of the frame to uncover the openings, each of the gates having intermediate its ends an inwardly extending arm extending through a longitudinally slotted portion of the frame, and spring means within the frame and connected to the inner end of each arm for retaining the arm within its respective slotted portion.

4. In a shaver of the class described, a frame having a wide end, an outer shear member of channel-shaped construction, positioned at said end of the frame with its flanges secured to the sides of the frame, said member having an open ended channel inwardly thereof parallel with the wide end of the frame, a hollow open-ended inner shear member reciprocally mounted within the channel, a long channel-shaped base positioned inwardly of the inner shear member and secured to and between the flanges of the outer shear member, the ends of the base being closed and provided with longitudinal slots, long gates reciprocally mounted at the opposite edges of the frame normally covering the open ends of the outer shear member and slideable backwardly therefrom to uncover said ends, said gates being provided with arms extending into said slots, and means slidably retaining said arms in said slots.

5. In a shaver of the class described, a frame having a wide end, an outer shear member of channel-shaped construction, positioned at said end of the frame with its flanges secured to the sides of the frame, said member having an open ended channel inwardly thereof parallel with the wide end of the frame, a hollow open-ended inner shear member reciprocally mounted within the channel, a long channel-shaped base positioned inwardly of the inner shear member and secured to and between the flanges of the outer shear member, the ends of the base being closed

and provided with longitudinal slots, long gates reciprocally mounted at the opposite edges of the frame normally covering the open ends of the outer shear member and slidably backwardly therefrom to uncover said ends, said gates being provided with arms extending into said slots, coil springs positioned longitudinally within the base and secured at their inner ends thereto, said springs being elongatable outwardly and provided at the outer ends with downwardly bent arms extending slidably through the inner ends of the arms of the gates.

6. In a shaver of the class described, a frame having a wide end, an outer shear member of channel-shaped construction, positioned at said end of the frame with its flanges secured to the sides of the frame, said member having an open ended channel inwardly thereof parallel with the wide end of the frame, a hollow open-ended inner shear member reciprocally mounted within the channel, a long channel-shaped base positioned inwardly of the inner shear member and secured to and between the flanges of the outer shear member, the ends of the base being closed and provided with longitudinal slots, long gates reciprocally mounted at the opposite edges of the frame in directions converging toward the shear end of the frame, said gates normally covering the open ends of the outer shear member and slidably backwardly therefrom to uncover said ends, said gates being provided with arms extending into said slots, coil springs positioned longitudinally within the base and secured at their inner ends thereto, said springs being elongatable outwardly and provided at the

25

30

outer ends with downwardly bent arms extending slidably through the inner ends of the arms of the gates.

7. In a shaver of the class described, a frame having a wide end, an outer shear member of channel-shaped construction, positioned at said end of the frame with its flanges secured to the sides of the frame, said member having an open ended channel inwardly thereof parallel with the wide end of the frame, a hollow open-ended inner shear member reciprocally mounted within the channel, a long channel-shaped base positioned inwardly of the inner shear member and secured to and between the flanges of the outer shear member, the ends of the base being closed and provided with longitudinal slots, long gates reciprocally mounted at the opposite edges of the frame normally covering the open ends of the outer shear member and slidably backwardly therefrom to uncover said ends, said gates being provided with arms extending into said slots, and spring means provided at the inner end of each arm for retaining the arm within the slots at the end of the base into which it extends.
